UNITED STATES PATENT OFFICE.

JOHN LARSON, OF TAMPA, FLORIDA.

DESIGN FOR TOY BIRD.

Application filed August 28, 1924. Serial No. 10,573. Term of patent 3½ years.

To all whom it may concern:

Be it known that I, JOHN LARSON, a citizen of the United States, residing at Tampa, in the county of Hillsborough and State of Florida, have invented a new, original, and ornamental Design for Toy Bird, as shown in the accompanying drawings and described

In the drawings, Figure 1 is the side perspective view of a toy bird constituting my new design, and Fig. 2 is a plan thereof.

I claim:

The ornamental design for toy bird substantially as shown.

JOHN LARSON.
